UNITED STATES PATENT OFFICE.

REINHOLD RÜDENBERG, OF BERLIN-GRUNEWALD, GERMANY, ASSIGNOR TO SIEMENS-SCHUCKERTWERKE GESELLSCHAFT MIT BESCHRANKTER HAFTUNG, OF SIEMENS-STADT, NEAR BERLIN, GERMANY, A CORPORATION OF GERMANY.

ELECTRIC DISCHARGE TUBE.

Application filed July 2, 1926, Serial No. 120,191, and in Germany June 26, 1925.

My invention relates to electric discharge tubes with gaseous cathodes.

In electric discharge tubes, more particularly in electron tubes operating with a quantitative relay effect, a gaseous or vaporous cathode may be employed by forming a discharge arc of mercury vapor, for instance by means of two auxiliary electrodes, and using said arc as cathode of the tube. 5 By the action of the potential difference between said arc and the anode of the tube the electrons are emitted from the arc space and reach the anode. Preferably the space containing the anode of the tube, or the 10 control electrodes respectively, is kept at lower pressure than the pressure within or about the vaporous cathode, since it is well known that the anode current may only be accurately controlled by the grid if the 15 evacuation in the control space has reached a certain value.

The object of my invention is to construct an electron tube of the above mentioned kind, by means of which it is possible to 20 maintain a sufficiently high vacuum in the space of the anode or of the control electrodes in spite of the fact that in addition to the electrons gaseous molecules also constantly escape from the cathode space 25 proper into the anode space.

According to my invention frictional resistances are interposed between the space of the cathode and that of the anode or control-electrodes respectively which resistances are cooled and are traversed by the 30 gas of the cathode passing into the anode space owing to a condensation or to a suction effect. A high-vacuum pump may for example be put in communication with the 35 anode space by means of which the gas is drawn through the frictional resistances from the cathode space into the anode space. The frictional resistances increase the difference of pressure between the cathode space 40 and anode space in such a manner, that a sufficiently high vacuum will prevail in the 45 space of the anode or of the control electrodes respectively. The electrons emitted from the discharge arc pass through the 50 openings of the frictional resistances to the anode. As frictional resistance a naturally porous diaphragm, or a diaphragm artificially provided with suitable openings may be employed. An embodiment of my in-

vention is diagrammatically represented, by 55 way of example, in the accompanying drawings, in which

Figure 1 represents a longitudinal vertical section through a discharge tube, and

Figure 2 represents a transverse section 60 on the line A—B Figure 1.

The electric discharge tube operating with a quantitative relay effect contains a cathode space 1, a space 2 for the anode 3 and a control grid 4. In the cathode space are 65 situated two auxiliary electrodes 5 and 6 for producing a mercury vapor arc acting as cathode. The auxiliary electrodes are supplied with direct current from a source 7. Between the anode space and the cathode space are inserted frictional resistance elements 8, which form between each other channels through which the gases are compelled to pass on their way from the cathode space into the anode space. From 70

the anode space the gases are drawn off by means of a discharge pipe 9 and a vacuum pump (not shown in the drawing). As already mentioned, the frictional resistances increase the difference in pressure between 80 the anode space and the cathode space in such a manner, that in the space of the anode a vacuum exists, which is sufficient for a quantitative relay effect. For example the pressure in the discharge arc of the mercury vapor may amount to about 10^{-3} mm., while in the anode space a pressure of 10^{-6} 85 mm. mercury column prevails.

Instead of sucking off the gases from the anode space by means of a pump, the gases 90 may also be condensed by cooling the anode space by a cooling jacket 10, which also surrounds the frictional resistance elements 8, thereby cooling them. The result of this expedient is that the major portion of the 95 vapor or other gaseous matter in passing through the resistance body is condensed at the elements 8 and thereby prevented from passing into the control electrode and anode space.

Various modifications and changes may be made without departing from the spirit and scope of the invention, and I desire therefore that only such limitations shall be placed thereon as are imposed by the prior 105 art.

What I claim as new and desire to secure by Letters Patent is:—

The combination with an electric discharge tube having a gaseous cathode, an anode and a control electrode between said cathode and anode, of frictional resistances inserted between the cathode and the control electrode and adapted to be traversed by the gases of the cathode passing into the

space of the control electrode, and means for cooling said frictional resistances, so that the gaseous particles, passing said resistances, are deposited on the latter. 10

In testimony whereof I affix my signature.

REINHOLD RÜDENBERG.
